UNITED STATES PATENT OFFICE

CARL J. H. DAVIS, OF MINNEAPOLIS, MINNESOTA

SHOE SHINING CABINET

Application filed September 26, 1931. Serial No. 565,324.

It is the object of this invention to provide a novel and improved shoe shine cabinet.

To this end, the invention consists in the novel parts and novel combinations of parts, hereinafter defined in the claims and described in the following specification, made in connection with the accompanying drawing, wherein like reference characters refer to the same or similar parts throughout the various views, and, in which,

Fig. 1 is a view in rear side elevation of a door to which a cabinet embodying the invention is applied, the cabinet being in closed condition and one section of the cabinet being broken away;

Fig. 2 is a vertical section taken on the line 2—2 of Fig. 1, as indicated by the arrows, showing the parts in collapsed and closed condition;

Fig. 3 is a similar vertical section showing the parts in extended condition for use; and

Fig. 4 is a horizontal section taken on the line 4—4 of Fig. 1, as indicated by the arrows.

Referring to the drawing, there is provided in accordance with the present invention, a cabinet consisting of two sections 5 and 6 respectively, secured together by hinges 7. Each of the two sections 5 and 6 form shallow trays and the section 5 carries at its ends brackets 5a to permit attachment of the cabinet to a support such as a door 8. The brackets 5a are applied to the section 5 adjacent the edge of the same remote from the hinges 7 and this section when applied as to the door 8, will always stand in substantially vertical relation.

Chains 9 or equivalent members are connected at their ends to the two sections 5 and 6 of the cabinet and these chains limit possible downward swinging movement of the section 6 relative to the section 5, so that when the section 6 is downwardly extended, it will extend substantially horizontally. A

pin 10 may be secured to the upper edge of one of the sections, as the section 5, while a hook 11 or equivalent latch member may be applied to the upper edge of the section 6 for cooperation with the pin 10 to hold the two sections together.

A block 12 is secured to the section 5 below the upper edge of the same and hinged to this block by means of the hinge 13, is an arm 14 covered by a strip 15 of rubber or similar friction material and forming a foot support. A bar 16 is hingedly connected by hinge 17 to an outer portion of the arm 14 remote from the hinge 13 and this bar 16 is, in turn, connected by a hinge 18 to a second bar 19. The hinge 18 swings in an opposite direction from the direction of swing of the hinge 17. The lower end of the bar 19 carries projecting pins 20. The two bars 16 and 19 comprise a toggle forming a brace for supporting the free end of the arm 14. A pair of laterally spaced upper blocks 21 are vertically spaced from a lower block 28, and the three blocks 21 and 28 are mounted in the section 5 adjacent the lower edge of the same and short vertical bars 22 connect blocks 21 to the ends of block 28. The blocks 21 and 28 together with the bars 22 and the side of section 5 form slots 23 within which the pins 20 are received. The slots 23 and pins 20 thus form a loose pivot which avoids the necessity of accurately proportioning the members 14, 16, and 19. Other blocks 24 are secured to the section 5 adjacent the ends of the same and bars 25 are secured at their ends to the blocks 24 and the bars 22. These bars 25 form racks for reception of such articles as a shoe brush 26, a can of shoe blacking 27, etc.

Preferably the cabinet will be secured to the inner side of a door, such as the door 8, so that when the door is closed, the cabinet cannot be seen. When it is desired to brush or shine shoes, the door 8 may be swung

open, whereupon the cabinet in collapsed condition as shown in Figs. 1 and 2, will be presented to view. The hook 11 may be unlatched from the pin 10, whereupon the section 6 may be swung downwardly from the position shown in Fig. 2 to the position shown in Fig. 3, whereupon the section 6 will be supported by the chains 9 in substantially horizontal relation. The free end 10 of the arm 15 may then be grasped and swung upwardly from the position shown in Figs. 1 and 2 to the position shown in Fig. 3, whereupon the brace formed by the bars 16 and 19 will assume the position shown in 15 Fig. 3. The movement of the brace from one position to the other may be readily accomplished due to the fact that the pins 20 are vertically slidable within the slots 23. Preferably the brace 16—19 will be of such 20 length that when the lower end of the bar 19 rests on the lower block 28, the arm 14 will be inclined downwardly somewhat from the horizontal. It will be seen that the foot of the user may be applied against the strip 25 15, whereupon the foot may be properly supported to permit shoe shining operations. As a shoe supported upon the arm 14 is being shined, the section 6 will catch any particles of dirt or polish that may be dropped 30 during the shining operation and thus the floor will not be soiled. When the shoe shining operations are completed, the cabinet may be folded up to its original position.

35 It will, of course, be understood that various changes may be made in the form, details, arrangement and proportions of the various parts without departing from the scope of the present invention.

40 What is claimed is:

A shoe shining fixture comprising a vertical support, an arm hinged at one end to the upper portion of said support, a toggle brace pivotally connected to the other end 45 of said arm, vertically disposed guide means attached to the lower portion of said support, and a member carried by the lower end of said brace and retained in slidable and pivotal relation within said guide means, the 50 lower end of said guide means being closed to limit the downward movement of the lower end of said brace whereby said arm and toggle brace can be collapsed against said support and said arm may be extended 55 outwardly from said support to cause said brace to hold said arm in extended position.

In testimony whereof I affix my signature.
CARL J. H. DAVIS.
